BOLT ANCHORING DEVICE

Herman Schmitt, Sheboygan, Wis.

Application May 19, 1939, Serial No. 274,629

3 Claims. (Cl. 72—101)

The invention relates to bolt anchoring devices particularly adapted for anchoring building elements to concrete foundations and the like, however applicable for general use for anchoring various devices to a concrete structure.

A further object is to provide a bolt anchoring device comprising a sleeve or socket adapted to be embedded in the concrete structure and having a threaded aperture therein for the reception of a bolt for holding or anchoring a building unit to the concrete structure.

A further object is to provide the outer periphery of the sleeve with annular interrupted ribs in spaced relation and between which the concrete is received for preventing the sleeve from being pulled from the concrete structure after the concrete has set.

A further object is to provide the outer periphery of the sleeve with downwardly flared grooves, into which grooves the concrete flows, and to upwardly taper a portion of the outer periphery of the sleeve thereby providing opposed angular surfaces for additionally anchoring the sleeve in the concrete.

A further object is to provide an anchoring device for concrete structures comprising spaced sleeves embedded in the concrete and having bolts threaded therein and bars through which the bolts extend into the sleeves, said bars having their ends overlapped for the reception of a swivel connection to which may be attached chains or other devices to be anchored.

With the above and other objects in view the invention resides in the combination and arrangement of parts as hereinafter set forth, shown in the drawing, described and claimed, it being understood that changes in the precise embodiment of the invention may be made within the scope of what is claimed without departing from the spirit of the invention.

In the drawing:

Figure 1 is a detail perspective view of a portion of a concrete foundation, showing the anchoring means for the lower bar of a building structure.

Figure 2 is a vertical transverse sectional view taken on line 2—2 of Figure 1.

Figure 3 is an enlarged side elevation of the sleeve.

Figure 4 is a perspective view showing the floor anchoring means.

Figure 5 is a bottom plan view of the sleeve or socket.

Figure 6 is a vertical transverse sectional view taken on line 6—6 of Figure 4.

Referring to the drawing, the numeral 1 designates a portion of the foundation of a building and 1^a a sleeper of the building frame disposed thereon. Heretofore various methods have been used to secure the sleeper to the concrete foundation, however they have been ineffective as the sleepers are not positively anchored. To overcome this difficulty a metallic socket 2 is provided, and which socket is embedded in the wall 1 before the concrete sets, clearly shown in Figures 1 and 2. The socket 2 is provided with a threaded aperture 3 into which aperture the securing bolt 4 is threaded after it is passed through the aperture 5 in the sleeper 1^a. The upper side of the sleeper 1^a is preferably provided with a recess 6 in which the bolt head 7 is received on the washer 8. It will be noted that after the concrete wall sets the sleeper 1^a can be easily and quickly attached thereto by the bolts. Only one bolt is shown, however, as many as desired may be used.

The socket 2 is cylindrically shaped for substantially two thirds of its length and terminates in a downwardly flared portion 9 at its lower end and is provided with spaced, annular interrupted ribs 10, between which ribs the concrete flows for securely anchoring the socket in the wall. It will be noted that the cylindrical portion and conical portion have their peripheries at angles to each other, thereby providing additional anchoring means for the socket. The outer periphery of the socket is provided with tapered grooves 11, in which grooves the concrete flows, therefore it will be seen that the socket will be positively anchored against rotation within the wall when tightening or loosening the bolts.

Referring to Figure 4, the anchoring means is shown in a floor 12, and the bolts 4 are shown extending through apertures of bars 13, which bars may be angularly placed in relation to each other if desired by passing the bolts through any of the apertures 14. The inner ends of the bars 13 are in overlapped relation, and secured together by a bolt 15 on the upper end of which is swivelly mounted a bifurcated member 16 having a bolt 17 adapted to extend through a chain link 18 or any other desired device to be anchored. A plurality of washers 19 are provided around the bolts for spacing the bars 13 from the concrete floor 12.

From the above it will be seen that an anchoring device is provided which is simple in construction and one wherein the anchoring socket is positively anchored in a plastic body

against axial movement as well as rotative movement.

The invention having been set forth what is claimed as new and useful is:

- 5 1. An anchoring device comprising sockets embedded in a concrete structure, bolts threaded into said sockets, bars secured to the sockets by said bolts, the inner ends of said bars being overlapped, a bolt extending through the overlapped ends of the bars and a pivoted shackle carried by said last named bolt.

2. A device as set forth in claim 1 wherein the bars are provided with means whereby they may be secured to the sockets when the sockets are at different distances from each other.

3. A device as set forth in claim 1 wherein the 5 bars are in the same plane and one of the overlapped ends of one of the bars is offset in relation to the other overlapped end of the other bar.
